(57) **CLAIM**

The ornamental design for a storage shelf, as shown and described.

DESCRIPTION

FIG. 1 is a front, top and right-side perspective view of the storage shelf showing my new design;

FIG. 2 is a front elevation view thereof;

FIG. 3 is a rear elevation view thereof;

FIG. 4 is an enlarged left side elevation view thereof;

FIG. 5 is an enlarged right side elevation view thereof;

FIG. 6 is a top plan view thereof;

FIG. 7 is a bottom plan view thereof; and,

FIG. 8 is a rear, bottom and left-side perspective view thereof.

The broken lines shown in the drawings illustrate portions of the storage shelf and environment that form no part of the claimed design.

1 Claim, 8 Drawing Sheets
